UNITED STATES PATENT OFFICE.

AMELIA POTVIN, OF DETROIT, MICHIGAN.

PUFF-HOLDING HANDKERCHIEF.

1,295,791.

Specification of Letters Patent.

Patented Feb. 25, 1919.

Application filed October 10, 1917. Serial No. 195,801.

To all whom it may concern:

Be it known that I, AMELIA POTVIN, a citizen of the United States, residing at Detroit, in the county of Wayne and State of Michigan, have invented certain, new and useful Improvements in Puff-Holding Handkerchiefs, of which the following is a specification.

This invention has as its object to provide 10 a handkerchief with means in the nature of a pocket for holding a powder puff so that the puff may be readily accessible and yet in the ordinary use of the handkerchief and, in fact, of the puff itself, will be concealed 15 from view, the pocket being arranged to completely cover and conceal the puff except that portion thereof which is actually to be employed.

Another aim of the invention is to so construct the pocket that the puff may be readily removed therefrom and placed therein so that the handkerchief may be laundered and an old puff may be replaced by a new one.

25 In the accompanying drawings:

Figure 1 is a perspective view illustrating one embodiment of the present invention;

Fig. 2 is a sectional view on the line 2—2 of Fig. 1;

30 Fig. 3 is a bottom plan view of the pocket.

In the drawings the handkerchief is indicated in general by the numeral 1 and in the pocket, indicated in general by the numeral 2, is formed by first gathering the material of the handkerchief by stitching, as indicated by the numeral 3, and then running a second line of stitching, indicated by the numeral 4, which latter line of stitching further serves to gather the handkerchief

along a circular line concentric to the gather 40 3. By thus gathering the material the same is so puckered as to form the said pocket 2 which pocket is substantially circular in shape and of a size to receive the puff which is indicated by the numeral 5. It will be 45 understood that inwardly of the gathering the pocket is of greater dimensions than at the opening formed by the said gathering and, consequently, a substantially circular powder puff inserted in said pocket will be 50 so engaged at its margin as to be securely held within the pocket although it may be readily removed when desired. It will further be observed by reference to Figs. 2 and 3 of the drawings, that all portions of the 55 puff are covered and concealed except that portion lying within the opening defined by the gathering and thus the presence of the puff within the handkerchief need not be made noticeable. It will be understood that 60 the pocket may be formed in the handkerchief at the center, as illustrated in Figs. 1 and 2, or it may be located at any other desired point.

It will be understood, of course, that the 65 pocket may be of some shape other than circular if desired and, of course, any desired size.

Having thus described the invention, what is claimed as new is:

As a new article of manufacture, a handkerchief gathered along an endless line to provide a pocket and stitched along said line through the gathers to permanently hold in place the said gathers to form the 75 mouth of the said pocket.

In testimony whereof I affix my signature.
AMELIA POTVIN. [L. S.]
